Ralph A. Rhoda, Orinda, Calif., assignor to Berkeley
Pump Company, Berkeley, Calif.

Filed May 8, 1972, Ser. No. 251,583

Term of patent 14 years

Int. Cl. D15—01

U.S. Cl. D77—1

FIG_1

FIG_2

FIG_3

FIG. 4

FIG. 5

FIG. 6

FIG. 1 is a one side elevational view of a water jet drive for boats showing my new design;

FIG. 2 is another side elevational view thereof;

FIG. 3 is a top plan view thereof;

FIG. 4 is a bottom plan view thereof;

FIG. 5 is one end elevational view thereof; and

FIG. 6 is another end elevational view thereof.

I claim:

The ornamental design for a water jet drive for boats, substantially as shown.
